Inventor.

Charly Sangalli

United States Patent Office.

CHARLES SANGALLI, OF NEW YORK, N. Y.

Letters Patent No. 84,844, dated December 8, 1868.

HAND-SUPPORTER FOR PIANOS, &c.

The Schedule referred to in these Letters Patent and making part of the same.

To all whom it may concern:

Be it known that I, CHARLES SANGALLI, of the city, county, and State of New York, have invented a new and improved Hand-Supporter for a Piano, Organ, or similar instrument; and I do hereby declare that the following is a full and exact description thereof, reference being had to the accompanying drawings, and to the letters of reference marked thereon.

The nature of my invention consists in providing a piano, organ, or other similar instrument, with a hand-supporter, which can at any time be attached or detached without injuring the instrument, as hereinafter described.

To enable others skilled in the art to make and use my invention, I will proceed to describe its construction and operation,

Figure 1 represents the hand-supporter in a full-view and elevated position. The red lines show the wooden frames of the instrument, to which are attached the braces S S, which maintain the hand-supporter above the key-board. B B are supports, which slide along the hollow rods A, by means of the friction-rollers O C. The two hands are placed into the stirrups I I, which serve as a resting-place for the same, leaving the fingers free to action. These stirrups can be made larger or smaller, to suit the dimensions of the hands, by means of the screw D, upon which move the nuts O' O'. J J are elastic bands, which can be raised or lowered through the buckles K K, or in any other appropriate manner. P P are flat plates, (which can be covered with leather, or any other fabric, so as not to injure the polished part of the instrument,) to receive the pressure of the screws E F.

Figure 2 shows the hand-supporter in a transversal section, passing through the instrument and apparatus. The screws E are used to fasten the hand-supporter to the upper frame of the instrument. G and H are two plates, which are used to maintain the position which

is desired to be given to the hollow rod A, which is shown in a section, and which can slide upon the whole length between the screws E and P. The other details of the construction are indicated by the same letters which are in fig. 1, but the hand is seen in the stirrup I, upon the keys of the instrument.

Figure 3 is the same hand-supporter, fastened to the lower frame of the instruments, formed below the key-board. In this position the stirrup I does not serve for the suspension of the hand, but as a rest to the wrist, as shown by the position of the hand in that figure.

Figure 4 shows a full view of the hand-supporter, placed in the position indicated in fig. 3, serving for a rest to the wrist. In this figure, the brace S, with the plates G H, the screws E F, the nuts O' O", and the counter-plates P P, are not shown. The frame B is placed upon the hollow rod A, by means of the two friction-rollers O C. The stirrup I is supported by means of the small pivot X X, and is movable. This view is the same as indicated in fig. 1, with the difference, that in the stirrup I, the elastic bands J J, which are seen in the interior, serve to rest the wrist, instead of suspending the hands.

What I claim as my invention, and desire to secure by Letters Patent, is—

The apparatus hereinabove described, or its equivalent, suspending the hands or resting the wrists, without hindering the free movements of the fingers, and keeping thereby the hand or wrist, and, in consequence thereof, the fingers upon the key-board, in the position desired, at the same time unhindering all the motions required to be made to use the same, and to play upon an instrument, as above described.

CHARLES SANGALLI.
